(57) **CLAIM**

I claim the ornamental design for a rug cutter, as shown.

DESCRIPTION

FIG. 1 is a left side elevational view of the design;
FIG. 2 is a bottom view of the design;

FIG. 3 is a rear elevational view of the design;

FIG. 4 is a right side elevational view thereof;

FIG. 5 is a top plan view thereof;

FIG. 6 is a front elevational view thereof; and,

FIG. 7 is a perspective view thereof.

The broken line showing of the blade is for illustrative purposes only and forms no part of the claimed design.

1 Claim, 3 Drawing Sheets

FIG. 2

FIG. 3

FIG. 7
